3,295,203
GRAPE AND FLOWER HARVESTING TOOLS
Raymond S. Thompson, 2044 E. Marsh St.,
Stockton, Calif. 95205
Filed May 25, 1964, Ser. No. 369,823
4 Claims. (Cl. 30—232)

My invention consists in a new and useful improvement in a grape and flower harvesting tool. The novel feature of my improved tool is the combination of three knife blades and means for mounting the tool on the thumb and index finger of the user.

While I show in the drawing and hereinafter fully describe one specific embodiment of my invention, it is to be understood that I do not consider my invention to be limited to said embodiment, but refer for its scope to the claims appended hereto.

In the drawing:

FIG. 1 is a perspective showing the tool applied to the hand of the user;

FIG. 2 is a bottom view of the tool.

As shown in the drawing, the tool has three knife blades 1, 2 and 3, connected by pivoting rivets 4 and having cutting edges 5. Blade 1 has thumb fitting flange 1a thereon. Blade 2 has a finger fitting flange 2a thereon. Blade 3 has a finger fitting flange 3a thereon. Blade 1 has a flange 1b with a cord 1c to encircle hand H.

As shown in FIG. 1, the tool is applied to the hand H by inserting thumb T in the flange 1a on blade 1 and the index finger F is in the flanges 2a and 3a on blades 2 and 3, respectively. The flange 1b and cord 1c fit around the hand H.

One of the great advantages of my improved tool is that it can be used on each hand and so allows picking and cutting to be done with both hands.

Since the tool has three knife blades pivotally connected, they are meshed against one another for cutting by merely closing the hand on which the tool is applied. This tool is much safer than an ordinary harvesting knife as its cut-

2

ting blades operate in such a manner that they cannot cut the user's fingers. It has been found that the tool allows much greater speed in harvesting than other cutting tools.

I claim:

- 5 1. In a harvesting tool for cutting plants, a combination of a first, second and third peat knife blades of about equal length, said first blade having means on its underside at one end for mounting on the thumb of a user and having means on its other end for a first freely pivotable connection to said second blade, said second blade having means at its end, remote from the said first pivotal connection, for a second freely pivotable connection to said third blade, said third blade having means on its underside for mounting toward the end of the index finger of the user, the cutting edges of the said blades being adapted to face each other when mounted on the hand of the user in a plane above the plane defined by the thumb and index finger.
- 10 2. A tool according to claim 1 in which mounting means are provided at said first pivotal connection for a cord to encircle the user's hand and mounting means are provided at said second pivotal connection for mounting to the lower portion of the index finger of the user.
- 15 3. A tool according to claim 1 in which said second blade has a cutting edge which bulges toward its central portion.
- 20 4. A tool, according to claim 1, in which said blades are connected by pivoting rivets.
